UNITED STATES PATENT OFFICE.

OTTO KURZ, OF CHICAGO, ILLINOIS.

MOP HOLDER AND WRINGER.

SPECIFICATION forming part of Letters Patent No. 605,961, dated June 21, 1898.

Application filed September 27, 1897. Serial No. 653,078. (No model.)

To all whom it may concern:

Be it known that I, OTTO KURZ, a subject of the Emperor of Germany, residing at Chicago, in the county of Cook and State of Illinois, have invented certain new and useful Improvements in Mop Holders and Wringers; and I do hereby declare the following to be a full, clear, and exact description of the invention, such as will enable others skilled in the art to which it appertains to make and use the same.

My invention relates to a novel construction in a mop holder and wringer, the object being to provide a device of this kind of simple, durable, efficient, and cheap construction and effective operation; and it consists in the features of construction and combinations of parts hereinafter fully described and claimed.

In the accompanying drawings, illustrating my invention, Figure 1 is a front elevation of a mop holder and wringer constructed in accordance with my invention. Fig. 2 is an end elevation of the same. Fig. 3 is a sectional view on the line 3 3 of Fig. 1. Fig. 4 is a detail sectional view of the lug for locking the crank-arm in its folded position, taken on the line 4 4 of Fig. 1.

Referring now to said drawings, A indicates a frame composed of an arched piece of sheet metal, the lower ends of which are recessed and form bearings for the shaft of a roller 1. Said arch A is bent to an inverted-V shape or angle-iron form, so as to give it greater strength without increasing the weight of my device.

On the upper middle portion of the said arch A a socket-piece 2 is mounted, which is adapted to receive a handle or stick 3. Adjacent its lower ends and on the inner face of said frame A guides 4 are mounted, in which the lower end portions of spiral springs 5 are adapted to move. Said springs 5 are situated within said frame A above said roller 1 and are composed of wires bent at their middle portions so that their end portions are parallel and the latter then bent to form a helix of a spiral spring, thus forming two springs each, which are connected by loops 6 at their lower ends. The other ends of said springs 5 enter openings in said socket-piece 2 and project into

the same, so as to enter recesses in the lower end of the handle or stick 3 and hold the same against removal. The shaft of said roller 1

passes through said loops 6 in said lower ends of said springs 5 and thence into the recesses 7 in the end portions of the frame A, where 55 they are journaled. Said loops 6 project beyond the lower ends of said frame A and serve as sliding bearings for the roller 8, thus keeping said roller 8 normally pressed into engagement with the roller 1 and forming a wringer. 60 The mop 9 is held between said rollers 1 and 8. Said shaft of said roller 8 is provided at one end with a flat projection or key 10, having two ears 11 and 12. The inner end of a crank-arm 13 is pivoted in said ear 11 and is 65 provided, adjacent said end, with a slot 14, which is adapted to receive said ear 12. Obviously when said ear 12 is in said slot 14 said roller 1 can be turned by said handle 13 and thus operate said wringer. When it is not 70

desired to use said crank-arm, the same is swung out of engagement with said ear 12 and into the position shown in full lines in Fig. 1, so that the handle 15 thereof lies above the adjacent portion of the frame A and out of 75 the way. Said crank-arm is locked in this position by means of a flat projection 16 on the adjacent side of said frame A, which is provided with two small recesses on its side edges and which is adapted to enter a slot 17 80 in said crank-arm and receive the wire composing the same in its recesses in an obvious manner.

Although I have shown the key 10 and arm 13 composed of wire, it will be understood 85 that I do not wish to be limited to the use of this material, as other materials could obviously be employed with equal advantage.

I claim as my invention—

1. A device of the kind specified comprising an arched frame provided with a socket-piece on its upper or arched portion and recessed at its ends, spiral springs mounted within said frame and provided with loops projecting beyond the ends of said frame, a 90 roller journaled in said recessed ends of said frame, a roller journaled in said loops of said springs and adapted normally to be held in engagement with said first-named roller, and a crank-handle on one of said rollers to turn 95 the same.

2. A device of the kind specified, comprising an arched frame provided with a socket-piece on its upper or arched portion adapted

to receive a handle, spiral springs mounted within said frame the upper ends of which enter openings in said socket-piece and recesses in said handle to hold the latter against removal, and the lower ends of which form loops which project below the recessed ends of said frame, a roller journaled in said recesses in said frame, a roller journaled in said loops and adapted to be held by said springs normally in engagement with said first-named roller, and a crank-arm on one of said rollers to turn the same.

3. A device of the kind specified, comprising an arched frame provided with a socket-piece on its upper or arched portion adapted to receive a handle, spiral springs mounted within said frame the upper ends of which enter openings in said socket-piece and recesses in said handle to hold the latter against removal, and the lower ends of which form loops which project below the recessed ends of said frame, a roller journaled in said recesses in said frame, a roller journaled in said loops and adapted to be held by said springs normally in engagement with said first-named roller, and a crank-arm pivotally mounted in one ear of a key on one of said rollers and provided with a slot adapted to receive the other ear thereof whereby said crank-arm can be placed in rigid engagement with said key to turn said roller.

4. A device of the kind specified, comprising an arched frame provided with a socket-piece on its upper or arched portion adapted

to receive a handle, spiral springs mounted within said frame the upper ends of which enter openings in said socket-piece and recesses in said handle to hold the latter against removal, and the lower ends of which form loops which project below the recessed ends of said frame, a roller journaled in said recesses in said frame, a roller journaled in said loops and adapted to be held by said springs normally in engagement with said first-named roller, and a crank-arm pivotally mounted in one ear of a key on one of said rollers and provided with a slot adapted to receive the other ear thereof, and a lug on said frame adapted to enter a slot in said arm and engage the same to lock said arm against said frame, substantially as described.

5. In a mop holder and wringer, a roller journaled within a frame and provided at one end with a key having two ears, a crank-handle pivoted in one of said ears and provided with a slot adapted to receive said other ear, a projection on the frame of said device, and a slot in said crank-arm adapted to receive said projection and engage the same to lock said crank-arm in a position folded against said frame when out of engagement with said last-named ear of said key.

In testimony whereof I affix my signature in presence of two witnesses.

OTTO KURZ.
